(21) Appl. No.: **29/153,525**

CLAIM

(22) Filed: **Jan. 10, 2002**

I claim the ornamental design for a replaceable extension tip
for a caulking gun, as shown and described.

(51) LOC (7) Cl. **08-05**

DESCRIPTION

(52) U.S. Cl. **D8/14.1**

FIG. 1 is a perspective view of the replaceable extension tip
for a caulking gun embodying the design of the present
invention.

(58) Field of Search D8/14.1, 14; D9/447;
222/566, 567, 568, 325, 340; 401/261;
215/235, 237, 239, 244

FIG. 2 is a front elevational view thereof;

(56) **References Cited**

FIG. 3 is a rear elevational view thereof;

U.S. PATENT DOCUMENTS

FIG. 4 is a side elevational view thereof;
